UNITED STATES PATENT OFFICE

157,446

TABLE SERVICE UNIT

Sidney H. Smith and James B. Selman,
Oklahoma City, Okla.

Application November 28, 1947, Serial No. 142,846

Term of patent 3½ years

(Cl. D44—24)

To all whom it may concern:

Be it known that we, Sidney H. Smith and James B. Selman, both citizens of the United States, residing at Oklahoma City, in the county of Oklahoma and State of Oklahoma, have invented a new, original, and ornamental Design for Table Service Unit, of which the following is a specification, reference being had to the accompanying drawing, forming part thereof.

The figure is an exploded perspective view of a table service unit, showing our new design.

We claim:

The ornamental design for a table service unit, as shown.

SIDNEY H. SMITH.
JAMES B. SELMAN.
